UNITED STATES PATENT OFFICE.

HERMAN PRATHER, OF JONESVILLE, INDIANA.

CORN-PLANTER.

SPECIFICATION forming part of Letters Patent No. 431,619, dated July 8, 1890.

Application filed April 19, 1890. Serial No. 348,697. (No model.)

To all whom it may concern:

Be it known that I, HERMAN PRATHER, a citizen of the United States, residing at Jonesville, in the county of Bartholomew and State 5 of Indiana, have invented a new and useful Improvement in Corn-Planters, of which the following is a specification.

My invention relates to an improvement in corn-planters, for which Letters Patent No. 10 418,747 were issued to me January 7, 1890.

The object of my present improvement is to provide improved means for raising and lowering the plow-beams on which the seed-dropping mechanism is mounted and for simultaneously throwing into and out of gear 15 the seed-dropping mechanism, whereby the working parts are reduced in number and simplified, all as hereinafter fully set forth.

The accompanying drawings illustrate my 20 invention.

Figure 1 represents a rear view of my planter, showing the plows in working position. Fig. 2 represents a side elevation of the same, the carrying-wheel being indicated in 25 dotted lines. Fig. 3 is a similar side elevation showing the plow-beam raised out of working position.

A is a wooden frame, which is mounted on an axle or shaft B, having a pair of carrying-wheels C C, one of which is secured to the 30 shaft so as to turn the shaft as the wheel moves forward.

D D are plow-beams hinged to and extending backward from the front beam of the 35 main frame A, and each carrying a plow E for opening the seed-furrow, and a seed-box F, provided with suitable well-known seed-dropping mechanism. The seed - dropping mechanism of each of the seed-boxes is actuated by the following means: A sprocket-wheel G is mounted on the axle or shaft B, so as to slide longitudinally thereon, and its hub is notched so as to engage a pin h, projecting from the axle in such a manner that 40 the sprocket-wheel will turn with the axle only when engaged with the pin. A second sprocket-wheel I, having a bevel gear-wheel J secured thereto, is mounted on a short stud k, mounted on the main frame and forming also one of 45 the hinges for the plow-beam.

Sprocket-wheels G and I are connected by a chain belt L, and bevel gear-wheel J is con-

nected with the seed-dropping mechanism by the shaft m and bevel gear-wheel n, mounted on the plow-beam. Sprocket-wheel 55 G is shifted into and out of engagement with pin h by means of a bell-crank lever o, mounted on the main frame and engaging a groove in the hub of the sprocket-wheel. Sprocket-wheel G is held normally in 60 engagement with pin h by means of a flat spring p, secured at one end to the main frame and with its free end pressing outward against the lower arm of lever o.

The mechanism thus far described is essentially the same as that shown in my former 65 patent, above mentioned. The mechanism therein shown for raising and lowering the plow-beam and for throwing into and out of gear the actuating mechanism of the seed-dropping devices being complicated and not 70 being fully controllable, I have invented the following mechanism for that purpose.

R is a lever, which is pivoted so as to swing in a vertical plane on a standard S, erected 75 on the main frame. The upper end of lever R is arranged within reach of the driver, sitting in the seat T, and the lower end of the lever is forked to form a hook u, adapted to engage the under edge of the upper arm of 80 lever o and a short arm v.

W is a short horizontal crank - shaft mounted so as to turn in bearings on the main frame and having its crank-arm provided with an eye x, which embraces the plow-beam. 85 Shaft W is also provided with a vertical arm y, which is connected with arm v of lever R by a link z, the arrangement of the parts being such that when the plow-beam is in working position lever R is in the raised position 90 shown in Fig. 1. A spring-catch t, erected on the main frame, is arranged to hook over the upper edge of lever R and hold it in position when depressed.

In operation, when the plow is in working 95 position lever R is raised, sprocket-wheel G is engaged with the pin h on the axle, and the seed-dropping mechanism is actuated as before described. When lever R is depressed so as to engage the catch t, arm y of shaft W 100 is drawn forward, thus partially rotating the shaft and raising the free end of the plow-beam and the plow. At the same time hook u engages and lifts the upper arm of lever o,

thus drawing the lower end of the lever o and sprocket-wheel G away from pin h and stopping the seed-dropping mechanism. By this construction only a few parts are required as compared with my former device, and the plow-beam is under more complete control of the operator.

I claim as my invention—

1. In a corn-planter, the combination, with the main frame and the plow-beam hinged thereto, of the crank-shaft W , mounted in bearings on the main frame, having its cranked end attached to the plow-beam and provided with arm y , lever R , pivoted to the main frame, and link z , all arranged to co-operate in the manner described and for the purpose set forth.

2. In a corn-planter, the combination, with the main frame, the axle having carrying-wheels secured thereto and supporting the main frame, the sprocket-wheel mounted loosely on the axle and adapted to engage a

projection on the axle, so as to revolve therewith, the spring arranged to hold the sprocket-wheel normally in engagement with the axle, the plow-beam carrying the seed-dropping mechanism, and intermediate mechanism connecting the seed-dropping mechanism and the sprocket-wheel, of the crank-shaft W , having arm y , and connected at its cranked end with the plow-beam, bell-crank lever o , mounted on the main frame and engaging the sprocket-wheel, lever R , also pivoted to the main frame and provided at its lower end with hook u and arm v , and link z , all arranged to co-operate as specified, whereby the plow-beam is raised and the sprocket-wheel is simultaneously disengaged from the axle, as and for the purpose set forth.

HERMAN PRATHER.
